[57] CLAIM

The ornamental design for controller for a game machine, as shown and described.

DESCRIPTION

FIG. 1 is a front perspective view of a first embodiment of a controller for a game machine in accordance with the my design;

FIG. 2 is a plan view of a controller of FIG. 1;

FIG. 3 is a left side elevational view of the controller of FIG.1;

FIG. 4 is a right side elevational view of the controller of FIG. 1;

FIG. 5 is a front elevational view of the controller of FIG. 1;

FIG. 6 is a rear elevational view of the controller of FIG. 1;

FIG. 7 is a bottom view of the controller of FIG. 1;

FIG. 8 is a front perspective view of a second embodiment of a controller for a game machine with my design;

FIG. 9 is a plan view of the controller of FIG. 8;

FIG. 10 is a left side elevational view of the controller of FIG. 8;

FIG. 11 is a right side elevational view of the controller of FIG. 8;

FIG. 12 is a front elevational view of the controller of FIG. 8;

FIG. 13 is a rear elevational view of the controller of FIG. 8; and,

FIG. 14 is a bottom view of the controller of FIG. 8.
